DESIGN FOR A COMBINATION CIGARETTE DISPENSER, LIGHTER, AND ASH TRAY

Ivar Jeppsson, Chicago, Ill., assignor to Chicago
Flexible Shaft Company, Chicago, Ill., a corporation of Illinois

Application January 31, 1934, Serial No. 50,571

Term of patent 7 years

To all whom it may concern:

Be it known that I, IVAR JEPSSON, a subject of the King of Sweden, residing at Chicago, in the county of Cook and State of Illinois, have invented a new, original, and ornamental Design for a Combination Cigarette Dispenser, Lighter, and Ash Tray, of which the following is a specification, reference being had to the accompanying drawing forming a part thereof.

The drawing is a perspective view of the cigarette dispenser embodying the design.

I claim:

The ornamental design for a combination cigarette dispenser, lighter and ash tray substantially as shown.

IVAR JEPSSON.
